UNITED STATES PATENT OFFICE.

ROBERT Z. FARMER, OF PORTLAND, OREGON.

SPRINKLER.

Application filed May 26, 1923, Serial No. 641,677.

To all whom it may concern:

Be it known that I, ROBERT Z. FARMER, a citizen of the United States, residing at Portland, in the county of Multnomah and 5 State of Oregon, have invented certain new and useful Improvements in Sprinklers, of which the following is a specification, reference being had to the accompanying drawings.

10 This invention relates to certain improvements in sprinklers and has relation more particularly to a device of this general character especially designed and adapted for use in the watering of lawns and the like and 15 it is an object of the invention to provide a novel and improved device of this general character embodying a rotary sprinkling head having associated therewith means whereby said head is caused to operate under 20 the influence of the pressure of the water passing through said head.

Another object of the invention is to provide a novel and improved device of this general character comprising a tubular stem 25 adapted for communication with a source of water under pressure together with a tubular head engaged therewith for free rotary movement and in communication with the stem, said head being provided with fins or 30 blades disposed over the inlet opening of the head whereby the force or pressure of the water entering the head serves to rotate the same.

The invention consists in the details of 35 construction and in the combination and arrangement of the several parts of my improved sprinkler whereby certain important advantages are attained and the device rendered simpler, less expensive and otherwise 40 more convenient and advantageous for use, as will be hereinafter more fully set forth.

The novel features of my invention will hereinafter be definitely claimed.

In order that my invention may be the 45 better understood, I will now proceed to describe the same with reference to the accompanying drawings, wherein:—

Figure 1 is a view partly in section and 50 partly in elevation illustrating a sprinkling device constructed in accordance with an embodiment of my invention and in working position;

Figure 2 is a sectional view through the 55 head taken substantially on the line 2—2 of Figure 1;

Figure 3 is a sectional view taken substan-

tially on the line 3—3 of Figure 2 looking in the direction of the arrow;

Figure 4 is a sectional view taken substantially on the line 4—4 of Figure 3 looking 60 in the direction of the arrows.

As disclosed in the accompanying drawings, 1 denotes a stake adapted to be forced in the ground and which is provided adjacent its upper end portion with a disc or 65 plate 2 to limit the extent of penetration of the stake 1. The stake 1 as herein disclosed extends above the disc or plate 2 and has engaged therewith a T-coupling 3. Operatively engaged with the stem or branch *a* of 70 the coupling 3 is a nipple 4 with which is adapted to be coupled or connected a hose *H* leading from a suitable source of water supply.

The head of the coupling 3 has engaged 75 therewith a tubular stem 5 of desired length and operatively connected with the upper end portion thereof is a nipple 6 having in swivelled connection therewith a sleeve 7.

The sprinkler head *S* constitutes a hollow 80 sprinkling member provided with an induction opening 8, said opening being defined by a depending sleeve 9 which is adapted to be threaded or otherwise engaged with the sleeve 7 whereby the sprinkler head *S* is supported by the stem 5 for free rotary movement. The wall of the head *S* as desired 85 points thereon is provided with a restricted eduction or discharge opening 10 through which the water is discharged and, by the rotation of the head *S* is evenly spread over the surface such as a lawn, to be sprinkled.

Immediately adjacent to the induction 90 opening 8, the head *S* is provided with the internal fins or blades 11 the same being integrally formed with the wall of said head. The blades are disposed on an incline of approximately 45° and are reversely related, the inner or meeting ends of the blades being positioned at substantially the axial center 100 of the opening 8, said blades crossing each other at a predetermined point inwardly of their outer margins. The points of connection of the fins or blades 11 are at opposite sides of the opening 8 but immediately adjacent thereto. As the water, which is under a certain degree of pressure, passes upwardly through the stem 5 and enters the head *S* the resistance offered by the fins or 105 blades 11 will result in desired rotation of the head *S* and in a manner whereby no hindrance or obstruction is offered to the

110

requisite discharge of the water through the openings 10. The speed or rotation of the head S will be dependent upon the flow of the water into the head S as offered by the 5 discharge through the openings 10.

From the foregoing description it is thought to be obvious that a sprinkler constructed in accordance with my invention is particularly well adapted for use by reason 10 of the convenience and facility with which it may be assembled and operated, and it will also be obvious that my invention is susceptible of some change and modification without departing from the principles and spirit 15 thereof and for this reason I do not wish to be understood as limiting myself to the precise arrangement and formation of the several parts herein shown in carrying out my invention in practice except as hereinafter 20 claimed.

I claim:—

A sprinkler comprising a tubular stem, a hollow sprinkler head, means for connecting the head to the stem to permit free rotation of the head, said head having an induction 25 opening in its wall in communication with the bore of the stem, internal blades carried by the head and oppositely inclined to partially overlie the induction opening, the adjacent ends of the blades being substantially 30 at the axial center of the induction opening, the outer marginal portion of each of the blades extending beyond the similar marginal portion of the second blade, said blades being carried by the wall of the head at opposite sides of the induction opening and immediately adjacent thereto.

In testimony whereof I hereunto affix my signature.

ROBERT Z. FARMER.
